(57) **CLAIM**

The ornamental design for a socket wrench, as shown and described.

DESCRIPTION

FIG. 1 is a front, plan view of the socket wrench, showing the new design;

FIG. 2 is a left side, end elevation view of the socket wrench from FIG. 1;

FIG. 3 is a right side, end elevation view of the socket wrench from FIG. 1;

FIG. 4 is a cross-sectional view of the socket wrench from FIG. 1 taken along line A-A';

FIG. 5 is a detail view of the socket wrench from FIG. 2 taken along lines B-B' and C-C';

FIG. 6 is a cross-sectional view of the socket wrench from FIG. 5 taken along line D-D'; and,

FIG. 7 is an exploded assembly perspective view thereof, showing the new design in a state of use with a needle valve for carburetors.

The broken lines shown in the drawings show unclaimed subject matter and environment only and form no part of the claimed design.
